UNITED STATES PATENT OFFICE.

GEORGE HEGENBERGER AND WILLIAM HEGENBERGER, OF DAVENPORT, IOWA.

SLEIGH-RUNNER.

SPECIFICATION forming part of Letters Patent No. 339,175, dated April 6, 1886.

Application filed February 16, 1886. Serial No. 192,060. (No model.)

To all whom it may concern:

Be it known that we, GEORGE HEGENBERGER and WILLIAM HEGENBERGER, of Davenport, in the county of Scott and State of Iowa, have invented certain new and useful improvements in Sleigh-Runners, of which the following is a specification.

Our invention relates to that class of sleigh-runners adapted to be secured to ordinary vehicles, and has for its object to so construct the runner as to give it the requisite strength and security against accidental displacement at a less cost than has been accomplished by means of prior constructions.

15 In the drawings, Figure 1 is a side elevation of our improved runner; Fig. 2, a top plan view; Fig. 3, a rear end view; Fig. 4, a longitudinal sectional view of the hub; Fig. 5, a section on the line $x-x$; Fig. 6, a section on the line $y-y$; Fig. 7, a modification.

A indicates the shoe, and B the rave, the two being riveted or fastened together at their forward ends in any suitable manner. A hub, C, is placed across rave B, preferably near the 25 rear end of the latter, and is secured thereto in a manner presently described.

D indicates a metallic band, which, after passing nearly around the hub C, is spread apart and extended down to the shoe A and bolted or otherwise secured thereto, thus forming a Λ -shaped brace, E, for the hub and rave, as well as for the rave and shoe. The band D is preferably made of flat iron and of about the same width as shoe A, and the 35 band may be secured to the hub by screws passing through the band into the hub, if desired. A bolt, e, serves to bind the band firmly upon the hub, as shown in Figs. 1, 3, and 5, and to further insure the retention of the band 40 in place it is set into the hub, as clearly shown in Figs. 2, 3, and 4.

F indicates another band, which also passes around the hub C, but at its outer end, as shown in Figs. 1, 2, 3, 4, and 6, the hub being 45 grooved for the reception of the band, as shown. This band, after passing about the hub, has its end bent outward slightly, as shown in Figs. 1 and 6, to form ears a and b, through which passes a bolt, f, binding the 50 band firmly upon the hub. Arms d extend from between the ears a b downward and

backward to the arms of brace E, as shown, and are secured to said brace by rivets or in any other suitable manner, thus forming a brace or support for the outer end of the hub C. 55

Instead of using two arms d and extending them to the brace E, a single arm may be found desirable in some cases, and when said single arm is used it will be extended down to the shoe A, as shown in dotted lines in Figs. 60 1, 3, and 4.

As shown in Fig. 7, the arms d d may be made integral with and as a continuation of the band F. The bolt f, binding the band F upon the hub, is extended forward to form a brace, 65 g, riveted to the rave B near its front end, as shown in Figs. 1 and 2, whereby the hub is steadied and maintained always at right angles to the shoe or runner. The bolt f is preferably provided with a jam-nut, h, as shown 70 in Figs. 1 and 6.

To assist in retaining the runner on the axle and prevent accidental displacement thereof should the axle-nut be lost, we adopt the construction shown most clearly in Fig. 4. 75

L indicates an angular metallic plate secured to the axle by means of the ordinary thill-clip, or by a special clip or other means, as preferred, the vertical depending portion of the plate being provided with a hole or 80 opening, i, as shown in Fig. 4. A rod, K, extends along the lower side of the hub C, and extends inward beyond the end of the hub, where it is furnished or formed with a hook, j, which passes through the opening i in plate 85 L, and engages over the edge of said opening. The rod K passes between the inner faces of the upper end of the brace E, and is secured thereto by the bolt e, which binds the band upon the hub, while the outer end of the 90 rod is clamped between the band F and the hub C, as shown in Figs. 4 and 6. The inner hooked end of the rod K must be so formed as to yield and allow its hooked end j to spring out of the hole i when it is desired to remove 95 the runner. The rave B is preferably let into the under side of the hub C, as shown, and to insure greater stiffness it may be screwed to the hub, as indicated in dotted lines.

Having thus described our invention, what we claim is—

1. In combination with shoe A and rave B,

a hub, C, resting upon said rave, and a band, D, passing about said hub and extended down to the shoe, substantially as shown.

2. In combination with shoe A, rave B, hub C, band D, and brace E, constructed substantially as herein described, band F and bracing-arms d d, integral with said band F.

3. In combination with shoe A, rave B, hub C, band D, and brace E, constructed substantially as described, band F at the outer end of the hub, arms d d, secured to said band and extending inward to form a brace or support for the outer end of the hub, and bolt f, passing through arms d d and extended forward to form a brace, g, as and for the purpose set forth.

4. In combination with an axle and a perforated plate secured thereto, a detachable runner constructed substantially as described and shown, and provided with a rod having a hooked end to engage the perforated plate. 20

5. In combination with an axle and a perforated plate secured thereto, the detachable runner provided with a rod having a yielding 25 hooked end, arranged and operating as described.

GEORGE HEGENBERGER.
WILLIAM HEGENBERGER.
